UNITED STATES PATENT OFFICE.

EDWARD C. MEIER, OF PHOENIXVILLE, PENNSYLVANIA.

SUPERHEATER CONSTRUCTION FOR BOILERS.

1,274,740.

Specification of Letters Patent.

Patented Aug. 6, 1918.

Application filed March 12, 1917. Serial No. 154,069.

To all whom it may concern:

Be it known that I, EDWARD C. MEIER, a citizen of the United States, residing at Phoenixville, in the county of Chester and State of Pennsylvania, have invented certain new and useful Improvements in Superheater Construction for Boilers, of which the following is a specification.

My invention consists of an improved superheater construction for boilers and is particularly adapted for use in connection with upright boilers including two or more boiler units.

One object of my invention is to provide a superheater structure in which the amount or degree of heat flowing thereto can be controlled.

Another object is to so construct the superheater structure that certain of the parts which comprise the superheater structure also assist in guiding or deflecting the products of combustion to the boiler units.

A further object is to so make my invention that it will be of simple construction and can be quickly and easily installed.

These objects, and other advantageous ends which will be described hereinafter, I attain in the following manner, reference being had to the accompanying drawings in which—

Figure 1 represents a sectional elevation of an upright boiler constructed in accordance with my invention.

Figs. 2 and 3 show sectional elevations of modified forms of my invention.

Referring to Fig. 1 of the drawings, 1 represents a boiler casing including two boiler units 2 and 3 of the upright type. The boiler unit 2 consists principally of drums 4 and 5 located respectively at the top and bottom thereof, and connected by a plurality of water tubes 6. These tubes 6 are inclined and receive heat from the fire box 7, the inclination of the tubes 6 being such that certain of said tubes extend upwardly and over the fire box, the drum 4 being located directly over the fire box while the drum 5 is located on one side of a wall 8 which projects above the bottom of the casing 1, and at the rear end of the fire box.

The boiler unit 3 is spaced from and to the rear of the boiler unit 2, and also consists principally of two drums 9 and 10 located respectively at the top and bottom thereof and joined by a plurality of water tubes 11.

The boiler unit 3 has a drum 9 located at a higher level than the drum 4 of the unit 2, and the drum 10 is located at a higher level than the drum 5 of the boiler unit 2 as in various forms of boilers of this type.

By this arrangement, the drum 9 forms the steam collecting drum and is connected by a series of pipes 12 with the drum 4. In like manner, the drum 5 is connected by a series of pipes 13 with the drum 10.

In carrying out my invention, I provide a baffle 14 which runs longitudinally of the pipes 6 of the boiler unit 2, and extends upwardly from the drum 5. This baffle is preferably made of a series of tile which rest upon one of the intermediate tubes of said boiler unit 2 and terminates short of the drum 4. I also provide a sectional baffle 15 which, at its lower end, connects the upper end of the baffle 14 and extends upwardly to provide a passageway for the products of combustion between it and the drum 4, said passageway being indicated at 16.

Another short divisional baffle 17 extends vertically and intersects the rear of the tubes 6, and extends beyond the upper end of the baffle 15. This baffle 17 stops short of the top 18 of the casing 1, and thus provides a passage 19 through which the series of tubes 12 pass.

Furthermore, by the above noted positioning of the baffles 15 and 17, a passage 20 is provided, the function of which will be hereinafter described.

A baffle wall 21 extends substantially vertical throughout a portion of its length, and at its top is slightly curved and intersects the drum 9. The lower end of the baffle wall 21 substantially intersects the rear tubes 6 of the boiler tube at a position above the drum 5 and is then turned in the form of an arch 22, said arch extending adjacent the forward tubes 11 of the boiler unit 3. Another baffle arch 23 is formed adjacent the uppermost tubes of the series of tubes 13 which connect the drums 5 and 10.

The boiler unit 3 has a longitudinally extending baffle 24 of the same general construction as the baffle 14 above referred to, and this baffle 24 extends from the drum 10 to a position below the drum 9. A rear baffle wall 25 extends downwardly to the rear of the tubes 11 and terminates at a position above the drum 10.

A damper or valve 27 consists of a plate which, as illustrated, is pivoted between its

ends and is designed to be turned into various positions between the upper ends of the baffles 15 and 17, and if desired, it can be turned into the dot-and-dash line position 5 in order to completely close the upper end of the passage 20. Thus by the provision of the baffles 15 and 17, the damper 27 and baffle wall 21, a superheating compartment is provided adjacent the top of the casing 1 10 and between the drums 4 and 9. This superheater chamber is formed between the drum 4 and baffle 15 and the drum 9 and upper part of the baffle wall 21.

A superheater 26 comprising a plurality 15 of convolutions of tube, projects into said compartment and between the upper portion of the baffle 17 and the upper portion of the baffle wall 21.

In operation, the products of combustion 20 within the combustion chamber 7 contact with the forward surface of the baffle 14, and pass upwardly into engagement with the drum 4 and through the passage 16, thus heating the drum 4 and the tubes of the 25 boiler unit which are located forward of the baffle 14.

The products after passing through the passage 16, enter the superheater compartment above referred to, and when the 30 damper 27 is open, a portion of said products will pass downwardly through the passage 20 and between the tubes 6 which are located to the rear of the baffle 14.

Another portion of the hot gases and 35 products of combustion passes through the superheater compartment and downwardly between the baffle 17 and the forward surface of the baffle wall 21, thence between the lower portions of the tubes 6 which 40 are located to the rear of the baffle 14. These products afterward pass through the passage provided between the arch 22 and the baffle 23, through the spaces between the tubes 11 which are located forward of the 45 baffle 24, and then upwardly into engagement with the drum 9 and through the passage provided between the upper part of the baffle 21 and the lower portion of the drum 9, and finally pass downwardly 50 between the baffle wall 25 and the rear face of the baffle 24, and then upwardly through the flue 28.

The damper 27, when in its closed position, causes all of the products of combustion 55 passing through the passage 16 to pass through the superheater compartment, and thereby engage the superheater and heat the steam therein to a high degree, it being noted that the superheater receives its steam from 60 the drum 9, and that the superheated steam passes outwardly through the pipe 29.

When it is desired to reduce the amount of 65 the products of combustion passing through the superheater compartment, the damper 27 is turned for example, into the position

shown in full lines in the drawing when a portion of the products of combustion will pass through the passage 20 instead of going through the superheater compartment.

It will be further noted that the damper 70 acts as a deflector and guides a portion of the products of combustion into the passage 20, and between the upper portion of the tubes which are located to the rear of the baffle 14.

It will be further noted that by having the baffle wall 21 extend downwardly and intersect the rear of the boiler unit 2, a contracted opening is provided at the bottom 75 whereby all of the products of combustion 80 are caused to pass between the rear tubes of the boiler unit 2, and that both the passage 20 and the lower portion of the superheater compartment communicate with the space between the rear face of the baffle 14 and the 85 forward face of the baffle wall 21.

It will be noted that the space between the baffle 17 and the front face of said baffle wall 21 forms a passage 30 which leads from the superheater compartment as does also the 90 passage 20. These two passages 20 and 30 lead downwardly from the superheater compartment and combine at their lower parts 95 so that the products of combustion passing through both of the passages 20 and 30 pass outwardly through the passage 31 which is formed between the lower end of the baffle wall 21 and the lower end of the baffle 14.

It will be further noted that the partition 17 also acts as a deflector to intercept 100 the products of combustion and thereby cause them to be deflected between the rear tubes of the boiler unit 2, and thereby cause the efficient heating of the same.

In the modification of my invention shown 105 in Fig. 2, I provide a chamber 32 immediately below the top of the casing 1 and between the boiler units 2 and 3. This chamber 32 is formed between the upper end of a baffle wall 33 and drum 9 and the drum 4 and 110 a baffle 35, a divisional baffle being located between the upper end of said baffle wall 33 and said baffle 35. The baffle 35 is of similar construction to the baffle 15 illustrated in Fig. 1 and extends at an incline to the tubes 115 of the forward boiler unit 2, it being noted that the boiler units 2 and 3 and their connecting drums and pipes are of similar construction to those described in connection with Fig. 1, and I have therefore given similar parts corresponding reference numerals.

The location of the baffle 34 between the upper portion of the baffle wall 33 and the baffle 35 not only serves to form the superheater chamber 32, but also provides a passage 36 which leads downwardly from the upper portion of the chamber 32 and under certain conditions permits the products of combustion or a certain portion of the products of combustion to pass downwardly between the 125 130

tubes of the boiler unit 2 which are located to the rear of a baffle 37, it being noted that the baffle 37 is of similar construction to the baffle 14 in Fig. 1.

5 The baffle 34 is substantially L-shaped in cross section and the lower leg thereof extends substantially parallel with a forwardly extending portion 38 of the baffle wall 33. The portion 38 substantially intersects the tubes of the boiler unit 2 and with said lower leg of the baffle 34 provides a passage 39 for the products of combustion after they pass downwardly from the superheater chamber 32.

10 15 The passage 39 is located adjacent the upper portion of the boiler unit, therefore any of the products of combustion passing therethrough will be caused to pass downwardly between the rear tubes of said boiler unit 2.

20 25 The baffle wall 33 also has a portion 40 which intersects with the forward end of the portion 38 and extends at an angle downwardly and adjacent the rear tubes of said boiler unit 2. This portion 40, at its lower end, extends rearwardly in the form of an arch 41, said arch terminating adjacent the forward tubes of the boiler unit 3.

25 30 A baffle 42 extends between the drums 5 and 10 in a manner similar to the baffle 23 above noted in connection with Fig. 1 and a baffle 43 is positioned between the tubes of the boiler unit 3 and extends upwardly from the drum 10.

35 35 It will be noted that the formation of the baffle wall including the portions 38, 40, and 41 provides a chamber 44 between the boiler units, this chamber being serviceable for a feed water heater.

40 45 A damper 45 is hinged at 46 to the top of the baffle 34 and is of such size as to extend to the upper end of the baffle 35 when entirely closed. This damper may be actuated by any means extending to the outside of the boiler casing, and serves to permit various amounts of the products of combustion to pass upwardly from the fire box 7 and downwardly through the passage 36.

50 55 It will be further noted that when the valve is open, that it serves as a deflector to cause some of the products of combustion to go downwardly through the passage 36 without affecting or engaging the superheater.

55 60 On the contrary, when the damper is closed, the arrangement of the baffles is such as to cause the gases and other products of combustion to come in contact with the superheater by passing first upwardly and then downwardly through the superheating compartment into the passage 39, thence forwardly into engagement with the uppermost portions of the rear tubes of the boiler unit 2, then downwardly between the baffles 37 and portion 40 of the baffle wall 33, and

thence between the arch 41, baffle 42, then upwardly between the baffle 43 and baffle wall 33 to heat the forward tubes of the boiler unit 3, then over the top of the baffle 43 and again downwardly between the rear tubes of the boiler unit 3, after which they pass upwardly and out the flue 28 in a manner described in connection with Fig. 1.

70 75 In Fig. 3 of the drawing, I have shown a boiler and superheater construction of the same general form as described in connection with Fig. 2 with the exception that I provide a baffle 47 instead of the baffle 35 above described.

80 85 The baffle 47 extends substantially at right angles to the tubes of the boiler unit 2 instead of at an incline as does the baffle 35 in Fig. 2. By thus arranging the baffle 47 at right angles, a less expensive construction is attained and for some purposes is 85 more desirable, since it permits a greater portion of the products of combustion to directly engage the uppermost portion of the superheater prior to passing downwardly through the superheater compartment. In 90 all other respects, the construction of Fig. 3 is similar to that described in connection with Fig. 2, and I have therefore given similar parts corresponding reference numerals.

95 It will be noted that by having the superheater arranged so as to extend downwardly from the top of the boiler casing into the superheater compartment as above described, that the superheater can be easily removed for purposes of repair.

100 105 In all of the constructions shown, the feed water enters the drum 10 through the medium of a pipe 48, said pipe at its upper end outside of the boiler having a valve 49 for regulating the amount of flow of the feed water.

110 115 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claim.

Having thus described my invention, what I claim as new and desire to secure by Letters Patent is:

120 The combination with a boiler casing, of front and rear boiler units spaced apart and including water tubes, a baffle wall between the units, said wall at its bottom having a portion adjacent the rear tubes of the front boiler unit and at its top having a portion adjacent the rear boiler unit, a baffle extending 125 longitudinally between the tubes of the front boiler unit, an angularly disposed baffle extending from the top of said longitudinal baffle to the rear tubes of said front unit, another baffle spaced between the rear tubes of 130

the front unit and the baffle wall and extending to a level below said latter angularly disposed baffle, for directing a portion of the products of combustion toward the 5 rear tubes of the front unit, a superheater having a portion extending between said spaced baffle and the baffle wall, and a damper positioned between the rear end of said angularly disposed baffle and the top

of the interposed baffle, substantially as de- 10 scribed.

In testimony whereof I have signed my name to this specification in the presence of two subscribing witnesses.

EDWARD C. MEIER.
